METHOD OF FORMING AXLE HOUSINGS

Joseph H. Gettig, Buchanan, Mich., assignor to
 Clark Equipment Company, Buchanan, Mich.,
 a corporation of Michigan

Application March 20, 1937, Serial No. 131,991

4 Claims. (Cl. 29—153.1)

This invention relates to axle housings and methods of forming the same, and is more particularly directed to the method of forming a rear axle housing of the type commonly employed in automotive vehicles, trucks, buses and the like.

The usual housing employed for this purpose is what is termed a banjo type housing having a central enlarged banjo frame section with extending tubular arms terminating in wheel bearing seats or in enlarged brake flanges and bearing seats through which the axle shaft extends. Such housings have been formed by taking a tubular blank, slotting the same at the central portion, expanding the central portion to form the banjo frame and swaging down the extending arms to the proper dimensions and upsetting or forging the wheel bearing seats at the extremities of the arms. This method of forming the housing requires that the tubular blank be of appreciable wall thickness throughout its length and of an appreciable diameter in order to provide sufficient metal for the expansion of the banjo frame, and thus requires that the arm portions be swaged down to a smaller diameter to accommodate the wheel bearing seats. The swaging operations are relatively expensive and require considerable time, as well as requiring a considerable investment in equipment.

The primary object of the present invention is to form a housing of this type from a flat rectangular blank of sheet stock or the like, which is operated upon in the flattened condition in such manner as to reduce the thickness of, and increase the area of the central portion while the blank remains flat, and to then form the blank into tubular shape with the arm sections of the proper diameter and wall thickness, and with the central portion enlarged and slotted for the expanding operation to complete the banjo frame.

In carrying out the present invention I contemplate taking a flat blank formed from strip stock such as boiler plate or the like, subjecting this blank to a rolling operation which corrugates the central portion thereof to produce longitudinally extending corrugations throughout the central portion. The blank thus formed is then subjected to a rolling operation which flattens out the corrugations to produce a laterally enlarged central section of reduced thickness which merges through tapered side edges into the arm portions of the housing. The flat blank thus formed is then slotted in the desired manner by a subsequent rolling operation, and is then subjected to a transverse bending operation to form

the same into a tubular shape having arm sections of the proper diameter and wall thickness, and a central tubular section provided with opposite longitudinally extended slots and of an enlarged diameter and decreased wall thickness. The tubular blank thus formed is then subjected to the usual expanding operations to form the banjo frame, and the extremities of the arms are then swaged or upset to complete the formation of the housing.

One of the main advantages secured by the present process is the elimination of the swaging operations on the arms, and the consequent reduction in cost and labor in producing the completed housing, as well as a considerable saving in the time required for producing the housing.

Another advantage secured by the present invention resides in the fact that the initial operations on the blank prior to the banjo expanding operation can be carried out in rolling operations which are relatively fast and more economical than previous machine operations for producing the same type of housing. In addition, by the present process the blanks can be continuously fed through the corrugating rolls, the flattening rolls, the slotting rolls and thence into the tube shaping machine as a continuous process, and thus greatly expedite the manufacture of the housing, while reducing the cost and time required as compared to previous operations.

Other objects and advantages of the present invention will appear more fully from the following detailed description which, taken in conjunction with the accompanying drawings will disclose to those skilled in the art the particular method in which an axle housing of the present invention may be formed.

In the drawings:

Figure 1 is a plan view of the flat blank after the first corrugating operation thereon;

Figure 2 is an end view of the blank shown in Figure 1;

Figure 3 is a plan view of the blank after the rolling operation which has extended its central area and reduced the thickness throughout the central section;

Figure 4 is a sectional view taken through the blank shown in Figure 3;

Figure 5 is a view of the blank after the rolling operation which forms the longitudinal slots;

Figure 6 is a sectional view taken substantially on line 6—6 of Figure 5;

Figure 7 shows the blank after it has passed through the preliminary tube forming phase of the process;

Figure 8 is an end view of the blank shown in Figure 7;

Figure 9 is an elevational view of the blank after it has been formed into tubular shape;

Figure 10 is a corresponding end view of the blank shown in Figure 9;

Figure 11 is an elevational view of one form of housing produced from the blank shown in Figure 9; and

Figure 12 illustrates a second form of housing formed from the blank shown in Figure 9.

Referring now in detail to the drawings, a flat blank of rectangular shape and of a wall thickness corresponding to that required in the arm sections of the axle housing is cut in sections of suitable length from flat strip stock or the like. This blank, indicated at 5 in Figure 1, is then passed through a series of corrugating rolls to produce the transverse corrugations 6 in the central portion 7 thereof, these corrugations terminating at approximately the point at which the throats of the completed banjo section will be disposed with reference to the extending arm portions 8 and 9. By the formation of the corrugations, the wall thickness of the intermediate portion 7 of the blank is reduced since the metal has been displaced in order to provide the increased surface area of the corrugations. The corrugated blank shown in Fig. 1 is then passed through suitable rolls which produce the blank shown at 10 in Fig. 3. This blank has arm sections 8 and 9 which remain the original thickness of the blank 5 as shown clearly in Figure 4, but has a planar central portion 12 of reduced thickness and of increased lateral surface, the portion 12 having a width substantially greater than the width of the arm sections 8 and 9, and joined to these arm sections by throat portions 13 which are of progressively increasing thickness toward the arm sections as shown clearly in Fig. 4.

The blank formed in the rolling operation as shown in Figs. 3 and 4 is then subjected to an additional rolling operation which produces depressed longitudinal portions 14 spaced on opposite sides of the longitudinal center of the portion 12 and extending for a substantial portion of the length of the section 12. These portions 14 are closed by thin web sections, indicated at 15 in Fig. 6, which, in the expanding operation are lanced and removed in order to accommodate entry of the expanding dies.

It is to be understood that the depressed sections 14 are not pierced entirely through the blank until after the tube forming operation, in order to preserve the strength of this portion and prevent distortion or crushing. This may be optional in the larger sizes of blanks having increased wall thickness. At present, I find it advisable to perform the flattening operations and the slotting operations as two separate and distinct operations.

The slotted blank, as shown in Fig. 6, may then be passed through the tube forming machine which will shape the blank initially into a substantially semicylindrical section, indicated generally in Fig. 7, the blank having the extending arm portions 8' and 9' which are of the same wall thickness as the portions 8 and 9 of the blank shown in Fig. 6. The enlarged central portion 12 of the blank shown in Fig. 6 is thus formed into the shape shown in Figs. 7 and 8 with the slots 14 disposed in diametrically opposed relationship centrally of the section 12. The throat portions 13 of the blank shown in Figs. 5 and 6

form the substantially frusto-conical sections 16 shown in Figs. 7 and 8, by which the thinned wall section of the portion 12 is joined to the thickened arm portions 8' and 9'. This operation upon the blank is accomplished by a series of 5 punch press operations in which a suitable die member is forced against the surface of the blank and bends the blank downwardly into a channel-shaped die opening to form it into the shape shown in Figs. 7 and 8, after which the blank 10 is subjected to a second die operation which closes the upper edges of the blank to produce the completed form of blank shown in Fig. 9.

The blank as shown in Figs. 9 and 10 has the abutting longitudinal edges welded as shown at 15 18 by any suitable means such as by atomic hydrogen welding equipment, by butt welding or flash welding through the use of any well known seam welding apparatus.

The blank as shown in Figs. 9 and 10 has the 20 extending arm portions 8' and 9' of the proper external diameter and wall thickness forming the completed banjo type axle housing, whereas the central portion 12 is of reduced wall thickness and increased diameter so that a smaller displacement of metal is necessary to form the completed 25 banjo frame section.

The blank of Fig. 9 is then placed in suitable expanding die members, substantially as described in Spatta Patent #1,925,850 issued September 5, 1933, and forms a cylindrical banjo section, indicated at 20 in Fig. 11, provided with the radially inwardly extending flanges 22 at opposite sides thereof and joined to the arm portions 8' and 9' through tapered throat portions 35 23 which progressively increase in wall thickness toward the arms substantially in accordance with the progressive increase in thickness shown at 18 in Figs. 4 and 6. The extremities of the arms 8' and 9' are subjected to successive swaging operations 40 which reduce the external diameter thereof and increase the wall thickness to provide wheel bearing seats, indicated generally at 24, adapted to support the hubs of wheel spiders mounted thereon when a full floating type of axle 45 housing is to be provided. Suitable brake retaining flanges 25 are welded to the arms 8' and 9' adjacent the extremities thereof and form suitable retaining means for the brake assemblies which cooperate with the wheels mounted 50 on the bearing seats 24. If desired, suitable spring pads may be secured to the arms 8' and 9' inwardly of the brake flanges 25 to form suitable supports for the springs by which the axle is supported from the vehicle. 55

When a passenger type axle housing is to be provided, the banjo portion 20 provided with the flanges 22 and the throat portion 23 is formed in a manner similar to that described in connection with Fig. 11; and the extending arms 60 26, corresponding to the arms 8' and 9', are subjected to endwise upsetting operations at their extremities to produce the enlarged thickened radial flanges 27 joined to the ends of the arms by the enlarged annular bearing seat portions 28. The inner surfaces of the portions 28 are suitably machined to receive the bearings for the axle shafts and, if so desired, suitable spring pads may be welded to the surfaces of the arms adjacent the bearing seat portions 28 to provide 70 suitable supports for the springs by which the housing is mounted from the vehicle.

It is therefore believed apparent that I have provided a simple and economical manner of forming an axle housing of the banjo type which 75

- eliminates the swaging operations heretofore found necessary, and which can readily be designed to provide a continuous process from the treatment of the original flat blank of uniform 5 wall thickness to the formation of the tubular blank having the central portion of increased diameter and decreased wall thickness, with the integral tubular extending arms with the proper external diameter and proper wall thickness.
- 10 I am aware that various modifications may be made in certain phases of the operations described herein, and therefore do not intend to be limited except as defined by the scope and spirit of the appended claims.
- 15 I claim:
1. The method of forming an axle housing which comprises providing a flat blank, transversely corrugating the central portion thereof, rolling said corrugations out to produce a central 10 section of enlarged surface and decreased thickness, rolling aligned transversely spaced oblong depressions therein on opposite sides thereof, forming said blank into tubular shape, expanding said central section to form a banjo frame section, and forming wheel bearing seats at the 15 extremities of the blank.
  2. The method of forming an axle housing which comprises providing a flat rectangular blank, rolling said blank to produce a series of 20 transversely spaced longitudinally extending corrugations only in the central portion thereof while maintaining the blank uniform in width, flattening the corrugated portion of said blank to produce a central portion of increased width 25 and decreased thickness merging into the unrolled portions of said blank through intermediate
- ate sections of tapering width and thickness, forming said blank into a tube having a central section of enlarged diameter and opposite tubular arms joined thereto through frustoconical sections, and expanding said central section into a 5 circular banjo frame with its axis normal to the axis of said arms.
3. The method of forming a blank for an axle housing which comprises transversely corrugating the central portion of an elongated rectangular sheet, rolling said corrugations out to form a flat sheet having laterally projecting surfaces at opposite sides of the central portion thereof, forming oblong shaped transversely spaced depressions in aligned positions in opposite surfaces 15 of said central portion, and forming said sheet into a tubular blank with the opposite longitudinal edges thereof welded together.
4. In the method of forming an axle housing from a single flat rectangular blank of a uniform 20 thickness equal to that desired in the arm portions of the housing, the novel procedure which comprises transversely corrugating the central portion of the blank and then flattening the same to increase the lateral surface of said portion and thereby decrease its wall thickness, the end portions of said blank merging into said central portion through tapered intermediate portions, and then pressing said blank into tubular shape with said central portion forming a 30 cylinder of increased diameter merging through intermediate frusto-conical sections of progressively increasing thickness into oppositely extending arm portions.

JOSEPH H. GETTIG. 35
